ERNEST HOPKINSON, OF NEW YORK, N. Y.

CARPET FABRIC AND METHOD OF MAKING SAME

Application filed August 2, 1930. Serial No. 472,581.

My present invention relates to an improved floor covering and the method of making the same.

Heretofore floor coverings, such as carpets or rugs, have been made of a fabric base with which is interwoven a pile, the whole constituting the well-known pile fabric of carpets or rugs. Due to the care necessary in manufacturing and to the quality of the material that must be utilized in such manufacture, the cost of such fabrics is relatively great. With a view to improving the manufacture of floor coverings, such as carpets or rugs, and to cheapen the cost of manufacture, while maintaining the quality, I have devised the subject-matter of the present invention.

In carrying out my invention, I preferably form a strand composed of a core of cord, or paper, or any other suitable material and having a covering of fibrous material wound or wrapped on the outside thereof. A plurality of such strands are laid side by side to form a layer of material and one side or face of this layer of material is coated with an aqueous dispersion of rubber, either natural or artificial or any other suitable adhesive material. Over the coating of adhesive material is preferably attached a layer of light fabric.

The above produces a floor covering at a minimum cost and is a satisfactory substitute for a pile fabric. My improved method, however, may be utilized in producing a pile fabric, either single faced or double faced. The procedure utilized in this form of the invention is to wrap a flat core of rubber, paper or any other suitable material with a layer of fibrous material, place a plurality of such cores side by side to form a layer of material of the desired length and breadth, cover each side or face of such layer of material with an aqueous dispersion of rubber, either artificial or natural or any other suitable adhesive, apply to the outer face of each layer of adhesion a fabric covering and then split the layer of material into two portions in a plane parallel to the fabric faces or coverings. There is thus produced two sections of floor covering which, when the cores have been removed constitutes a true pile surface.

Where the cores are of rubber, they may be removed before the splitting operation takes place. Should it be desired to produce a double faced pile fabric, the fabric layer above referred to is omitted, the material split in the manner described and the two adhesive coverings are placed together thus producing a double-faced pile material.

The object of my invention, therefore, is an improved floor covering and method of making same.

In the accompanying drawings, illustrating the preferred embodiment of my invention;

Figure 1 is a perspective view of one modification;

Fig. 2 is an end elevation of one of the elements utilized in the formation of Fig. 1;

Fig. 3 is a section of another modification;

Fig. 4 is a view similar to Fig. 3, but to be utilized in the building of a two-faced pile material;

Fig. 5 is one of the units obtained from a splitting of Fig. 4 and

Fig. 6 is a view showing a double pile fabric made from a plurality of the elements shown in Fig. 5.

Referring to the drawings, and particularly to Figs. 1 and 2, 10 designates a core of fibrous material such as cord or paper. On this core is wrapped a layer 11 of fibrous material such as cord or loose fibers. Each of these wrapped strands or yarns is made of substantially equal length and are then arranged parallel to each other as shown in Fig. 1 forming a layer of material of the thickness equal to the diameter of the core 10, plus twice the thickness of the strand 11. One face of this layer is then coated with an adhesive material 12, such as a dispersion of rubber, either natural or artificial, and a covering layer 13 of fabric is applied thereto. The cords may be directly applied in parallel arrangement to the layer of fabric, which has been previously coated with a rubber material, preferably a natural or artificial latex. These methods of operation or manufacture produce a floor covering such as carpet or rugs of substantial thickness and of relatively long life. Also, the material is resilient.

due to the character of the core 10 on which the various elements are wound.

Referring now to Fig. 3, there is shown a plurality of cores 14 substantially rectangular in cross section and of any desired material such, for example, as rubber. These cores 14 have wound thereon layers 15 of fibrous material similar to the fibrous material 11 in the modification above described, and a plurality of such wrapped cores 14 are arranged parallel to each other as shown in Fig. 3 to form a layer of material of the desired length and breadth and of the proportionate thickness shown. Each face of this layer is coated with an adhesive 16, for instance one comprising a dispersion of rubber, either natural or artificial and such layers of adhesive are covered with fabric layers 17. In the case where the cores 14 are rubber the cores are easily removed from the layer of material either before or after the coating operation takes place, but where the cores are of a material other than the rubber it may be found preferable to leave such cores in place. The layer of material is then split in a plane midway between the layers of fabric 17 or on the plane designated by the numerals 18-18. After the splitting operation, the cores 14 may be removed and the resultant fabric is a pile fabric suitable for upholstery or floor covering.

In some cases it is preferable to produce a double faced material and in this event the method as outlined with regard to Fig. 3 is pursued up to and including the application of the adhesive layers 16. Referring to Figs. 4, 5 and 6, it will be noted that the fabric layer 17 of Fig. 3 has been dispensed with and the splitting operation on the plane 18-18 is midway between the outer surfaces of the layer 16 of the adhesive material. The splitting of the composite structure and the subsequent removal of the cores 14 results in the formation of two pieces of pile fabric, such as shown for example in Fig. 5. The two pieces may be used as such or may be backed together with an adhesive layer as shown in Fig. 6 producing a pile fabric with double face.

While I have described my invention as applicable to the production of specific types of floor coverings and pile fabric materials, it is to be understood that my invention is not to be thus limited, and that it may be used in a variety of ways and for the production of a variety of materials without departing from the spirit of the invention.

Subject matter not claimed in this application is described and claimed in my co-pending application Serial No. 404,457, filed Nov. 2, 1929.

Having thus described my invention, what I claim and desire to protect by Letters Patent is:

1. That improved method of making a pile

fabric which consists in wrapping fibrous material about a core, placing a plurality of wrapped cores side by side to form a layer of material, applying adhesive backing to both sides of the layer of material, removing the cores and then severing the fibrous material in a plane between the adhesive backings. 70

2. That improved method of making a pile fabric which consists in wrapping fibrous material about a core of resilient material, placing a plurality of wrapped cores side by side to form a layer of material, applying a backing of fabric and adhesive material to both sides of the layer of material removing the cores and then severing the fibrous material in a plane parallel to the backing. 75 80

3. That improved method of making a pile fabric which consists in wrapping fibrous material about a flat core, placing a plurality of wrapped cores side by side to form a layer of material, attaching a backing to both sides of the layer of material removing the cores and then severing the fibrous material in a plane side by side and between the backing layers. 85 90

4. That improved method of making a pile fabric which consists in wrapping fibrous material about a core, arranging the wrapped core in layers contiguous to each other to form a layer of material, attaching an adhesive backing to both sides of the layer of material, severing the fibrous material in a plane parallel to the backing and between the backing layers and removing the core. 95

5. That improved method of making a pile fabric which consists in wrapping fibrous material about a core, arranging the wrapped core to form a layer of material, attaching a backing of adhesive and fabric to both sides of the layer of material, and severing the fibrous material in a plane parallel to the backing and between the backing layers. 100 105

6. The method of making pile fabric which consists in wrapping fibrous material about a core, placing a plurality of wrapped cores side by side to form a layer of material, applying an adhesive film to both faces of the layer of material, severing the composite whole on a plane midway between the said faces and then attaching together the two 110 115 pile fabrics so cut to form a double faced pile fabric.

Signed at New York city, county of New York, State of New York, this 29th day of July, 1930.

ERNEST HOPKINSON.
